OLGA BERGHORN, OF TEANECK, NEW JERSEY

SHEATH FOR CIGARETTE PACKAGES

Application filed July 5, 1929. Serial No. 375,968.

My invention relates to a novel convenience and sales-aid for application to cigarette packages. The novel feature is a paper sheathe into which a complete cigarette packet may be slipped, this sheathe carrying a supply of matches on one side beneath a flap formed from the strip of paper of which the sheathe is composed. The opposite side of the sheathe is plaited so as to afford a pocket, adapted to receive a stick of chewing gum, a piece of mint candy or other small article or articles.

The object of the invention is to provide at very slight expense an adjunct calculated to promote the sale of a brand of cigarettes, more particularly those which are put up in soft paper packets. It is customary to give away a paper book of matches with a package of cigarettes, and the cost of the sheathe of the present invention with its match supply need be little if any greater than the cost of a match book. The inclusion of a small stick of gum or the like in the sheathe or supplementary wrapper is an inconsequential item of cost, adding greatly to the salability of the package.

The invention has special advantage in connection with the sale of cigarettes by vending machines, since it delivers cigarettes and matches, and optionally the additional premium, in one compact package suitable for such machines.

The sheathe also affords a large amount of extra surface for advertising and display matter. The cigarette packet, complete in itself, will carry the usual printing and designs characteristic of the particular brand, and the sheathe will afford an equal amount of surface. If the customer does not care to keep the sheathe on the package, he or she simply slips it off, and the normal package remains. This is an important consideration to the cigarette manufacturer.

In the accompanying drawings forming part hereof:

Fig. 1 is a plan view of a package of cigarettes with the sheathe of this invention on it;

Fig. 2 is an end view; and

Fig. 3 is a perspective view of the sheathe itself.

The numeral 2 designates an ordinary cigarette package of the soft paper, or paper and foil, type, 3 being the revenue stamp by which the packet is sealed.

The sheathe 4 is made from a single flexible strip of paper, which is curved or bent into tubular form corresponding to the oblong shape of the cross-section of the package, and of such size as to slip on and off readily and to stay in place by virtue of light friction. The end portions of the strip are glued or otherwise fastened together at 5 and 6, or they may be glued together continuously between these regions. A flap 7 is formed, which covers one of the broad sides of the sheathe and preferably extends part way over one of the narrow sides, where it is secured by a sticker 8. This flap is preferably, though not necessarily of double thickness.

On the broad side of the sheathe covered by the flap, there is secured by stapling or otherwise a clip of paper matches 9, together with the usual striking surface 10. The matches are completely and safely covered by the flap.

The opposite wide side of the sheathe is plaited lengthwise in an internal box plait 11, which forms a flat open-ended pocket adapted to retain a stick of gum 12 or other premium. This plaited pocket is kept from opening out by a sticker or seal 13 or other suitable means.

From the foregoing it is believed that the nature and advantages of the invention will be apparent. Details may be modified.

In a general aspect, the invention provides a match-carrying wrapper for a cigarette package, such wrapper also preferably containing a pocket to hold a premium. Chewing-gum, mint candy or some breath sweetening or purifying confection or the like is desired by many persons after smoking; consequently the inclusion of such a premium in the wrapper is calculated to increase the popularity of any given brand of cigarettes. This feature may also be used without the match feature.

I claim:

1. An article of the character described, comprising a paper strip formed into a sheathe adapted to receive a cigarette packet and a flap to cover one side of the sheathe, a supply of matches mounted on said side of the sheathe and covered by said flap, the opposite side of said sheathe having a plait forming an external pocket, and means for securing said plait.
- 10 2. An article of the character described, comprising a paper strip formed into a sheathe adapted to receive a cigarette packet, one side of said sheathe having a plait forming an external pocket, and means for securing said plait.
- 15 3. An article of the character described, comprising a paper strip formed into a sheathe adapted to receive a cigarette packet, one side of said sheathe having an internal box plait forming an external pocket, and means applied to the outer sides of said plait to hold the same closed.

OLGA BERGHORN.
